UNITED STATES PATENT OFFICE.

ALFRED HATCH BRADLEY, OF NEW ORLEANS, LOUISIANA.

GRASS-BURNER FOR RAILWAY-TRACKS.

No. 920,721.

Specification of Letters Patent.

Patented May 4, 1902.

Application filed January 13, 1900. Serial No. 473,024.

To all whom it may concern:

Be it known that I, ALFRED HATCH BRADLEY, a citizen of the United States of America, residing at New Orleans, in the parish of Orleans and State of Louisiana, have invented certain new and useful Improvements in Grass-Burners for Railway-Tracks, of which the following is a specification, reference being had therein to the accompanying drawing.

This invention relates to grass burners for railway tracks, and is designed as an improvement in my Patent No. 451,218 granted to me April 28, 1891.

The object of the invention is to provide novel and peculiar means for supplying gas to the grass burners or gas jets.

A further object of the invention is to provide novel and peculiar gas generating apparatus, and a special system for generating gas and for connecting the generator with the gas jets or grass burners.

A still further object of the invention is to provide special pipe connections between a gas generator and a source of steam, air and oil supply carried by a car or engine.

In the accompanying drawings forming part of this application: Figure 1 is a side elevation of part of a car truck showing the application of the invention in section. Fig. 2 is a top plan view partly broken away. Fig. 3 is an end view partly broken away. Fig. 4 is a detail elevation of the jet-tank. Figs. 5 and 6 are detail elevations of the spray-nozzle.

The same reference numerals denote the same parts throughout the several views of the drawings.

For purposes of exemplification the invention is shown applied to a bed 1 of a flat railway car. A tank or other suitable inclosure 2 has a partition 3 inclined from its center and divides the tank into a gas reservoir 4 and an oil reservoir 5. The center of the partition 3 is provided with a ball check-valve 6, and the top of the tank has a similar valve 7. Said top having ordinary safety valve 8, and hand-hole 9.

Hot air is supplied to the reservoirs 4 and 5 from a supply pipe 10, having a branch pipe 11 extending into the reservoir 4 and terminating in an air-jet 12 under the valve 7; and a branch pipe 13 extending through the partition 3 downwardly through a body

of oil 14 in the reservoir 5 and terminating in a spray-nozzle 13^a at the bottom of the reservoir 5, whereby the oil is supplied with hot air.

The pipe 11 is provided with a suitable valve 15, and the pipe 13 has a similar valve 16. An oil supply pipe 17 has a branch pipe 18 for carrying oil into the reservoir 5, and is controlled by a valve 19. A steam supply pipe 20 is connected, by means of a valve 21 and its coupling, to a coil pipe 22, immersed in the oil within the reservoir 5, for heating the oil contained in the reservoir 5. One end of the coil 22 is connected to the oil supply pipe 17 by a branch pipe 23 having a suitable valve 24, and the other end of the coil 22 extends through the wall of the reservoir 5 and is coupled to a gas pipe 25, which connects the reservoir 4 through its valve 7 with a tank 26, having gas-jets 27 provided with regulating keys or valves 28.

It is obvious that the valve 19 is only opened when necessary to supply the reservoir 5 with oil, and that the valve 24 is operated to charge the steam coil with a certain amount of oil for mixing with the steam as it is conveyed to the gas pipe 25. The check valves 7 and 6 are operated respectively by air from the air-jet 12, and by vapor or gas rising from the body of oil in reservoir 5, so that the pipe 25 is first supplied with gas, and then steam is introduced into the pipe 25, whereby a mixture of gas and steam is fed to the jet-tank for burning through the jets.

It will be seen that the operation of feeding gas and steam together into the jet-tank is automatic, and that there is no oil fed to the jets, and therefore the rails are not oiled or greased by using the burner. It is obvious that the air and steam may be supplied from a locomotive or motor car, and that the oil may be supplied from a storage tank on such car.

Having thus described my invention what I claim as new and desire to secure by Letters Patent is:

1. In a grass burner for railway tracks, the combination, with a tank having a valved top and adapted to be carried by a locomotive or railway car, a valved partition separating said tank into gas and oil reservoirs, and a jet-tank, of a pipe connecting the top valve with the jet-tank, a steam pipe coiled within the oil reservoir and coupled to said

connecting pipe, air supply pipes to each reservoir, and oil supply pipes.

2. In a grass burner for railway tracks, the combination, with a tank, a check valve in the top thereof, a partition separating the tank into gas and oil reservoirs, a check valve in the partition, a jet-tank, and a pipe connecting the said top valve with the jet-tank, of an air supply pipe having branches, 10 one of which discharges into the gas reservoir, and the other of which discharges into the oil reservoir, a steam pipe coiled in the oil reservoir and coupled to the said connecting pipe, an oil supply having branches one of 15 which opens into the oil reservoir and the other of which is connected to the said steam pipe, and suitable valves in the various branch pipes.
3. In a grass burner for railway tracks, the 20 combination, of a gas generating tank having

a partition dividing the tank into gas and oil reservoirs, a check-valve in the partition and operated by gas pressure from the oil reservoir for opening and closing communication between the reservoirs, a check-valve in the top of the gas reservoir and operated by air pressure from within the gas reservoir, a jet-tank connected with the said top valve, a steam pipe extending through the oil reservoir and connected with the jet-tank, means 25 for supplying both reservoirs with air, and suitable means for supplying one of the reservoirs and the steam pipe with oil.

In testimony whereof I affix my signature in presence of two witnesses.

ALFRED HATCHI BRADLEY.
